UNITED STATES PATENT OFFICE

MORRIS H. BLOCK, OF DENVER, COLORADO, ASSIGNOR TO HARRY KORTZ, DAVID A. BLOCK, AND PHILLIP KLEIGER, OF DENVER, COLORADO

DESIGN FOR A NURSING BOTTLE

Application filed June 25, 1932. Serial No. 44,194. Term of patent 14 years.

To all whom it may concern:

Be it known that I, MORRIS H. BLOCK, a citizen of the United States, residing at the city and county of Denver, and State of Colorado, have invented a new, original, and ornamental Design for a Nursing Bottle, of which the following is a specification, reference being had to the accompanying drawing, forming part thereof, in which—

Fig. 1 is a perspective view

Fig. 2 is an elevation, and
Fig. 3 is a plan view.

I claim:

The ornamental design for a nursing bottle, as shown.

In testimony whereof he affixes his signature.

MORRIS H. BLOCK.
